ROTARY ENGINE

George E. Mallinckrodt, St. Louis, Mo., assignor to Elliot Enterprises, Incorporated, St. Louis, Mo., a corporation of Missouri

Application December 3, 1956, Serial No. 625,978

17 Claims. (Cl. 121—49)

This invention relates to rotary engines of the type in which several rotating systems (having alternating pistons) interchange angular momentums during certain reverse-locking events, and between which systems certain expansion events cause the systems to overrun one another alternately to supply power to a shaft through power integration means.

Among the several objects of the invention may be noted the provision of means for producing in a greater range of engine sizes reliable interchange of piston positions during reverse-locking events preparatory to expansion events; the provision of means of the class described which is hydraulic in character, being adapted for compact design, self-lubrication and trouble-free mechanical operation; the provision in such apparatus of a hydraulic collision process for assisting and controlling a gaseous collision process in transferring momentum from one rotating system to the other, whereby thermodynamic operation may be improved; and the provision of smooth and stable performance characteristics in machines of this class. Other objects and features will be in part apparent and in part pointed out hereinafter.

The invention accordingly comprises the elements and combinations of elements, features of construction, and arrangements of parts which will be exemplified in the structures hereinafter described, and the scope of which will be indicated in the following claims.

In the accompanying drawings, in which one of various possible embodiments of the invention is illustrated,

Fig. 1 is a partial longitudinal jogged section of an engine embodying the invention, being taken on line 1—1 of Fig. 2, some of the parts at the left which are the same as parts shown at the right, being omitted;

Fig. 2 is a cross section, taken on line 2—2 of Fig. 1, the engine being shown in an intermediate position of parts;

Fig. 3 is a cross section taken on line 3—3 of Fig. 1;

Fig. 4 is a developed view of section 4—4 of Fig. 2;

Fig. 5 is a developed view of section 5—5 of Fig. 2;

Fig. 6 is a skeleton diagram of parts corresponding to their neutral positions shown in Fig. 2, wherein one rotor is advancing upon the other rotor, the latter being reverse locked;

Fig. 7 is a view similar to Fig. 6, showing further advance of the one rotor relative to the reverse-locked rotor;

Fig. 8 is a view similar to Fig. 7 but showing further advance of the one rotor and retreat of the other from reverse-locked position; and,

Fig. 9 is a view of a position of parts similar to Fig. 6, except that the rotor positions have been interchanged.

The stippling shown in Figs. 1, 2 and 6—9 is arbitrary and for the purpose of diagrammatically distinguishing one connected set of pistons A, B, C, D, L, M and grooves P, Q on rotor 31 from an unstippled set of connected pistons W, X, Y, Z, N, O and grooves R, S on rotor 29.

2

In diagrammatic Figs. 6—9 the unstippled pistons W, X, Y, Z, N, O and grooves R, S on rotor 29 are dotted as a further distinction.

Corresponding reference characters indicate corresponding parts throughout the several views of the drawings.

Referring now more particularly to Fig. 1, there is shown at numeral 1 a stationary ring to which cylinder heads 3 and 5 are attached by means of through bolts 8. Parts 1, 3 and 5 form an annular or toroidal cylinder generally numbered 7. The ring 1 is provided with a jacket 9 to form a water-cooling space 11. The cylinder heads 3 and 5 are formed with necks 13 and 15, respectively, in which are press-fitted, angularly fixed flanged liners 17 and 19, respectively, held in proper axial press-fitted positions by adjusting nuts 21 and 23, respectively threaded to the necks 13 and 15. The flanges of the liners are numbered 25 and 27, respectively, their inside faces being fixed and substantially flush with the inside faces of the cylinder heads 3 and 5.

Located between the flanged portions 25 and 27 are abutting rotors 29 and 31. These have hollow quills 33 and 35, respectively, extending through and out from said liners 17 and 19. Within the quills 33 and 35 are bearing sleeves 37 and 39, on a power shaft 41 extending axially through the machine. These sleeves 37 and 39 form bearings for the rotor quills 33 and 35, respectively.

Carried on the rotor 31 and extending in an axial direction over the outside of the rotor 29 are power pistons A, B, C and D (Fig. 2). Carried on the rotor 29 and extending in an axial direction over the outside of the rotor 31 are power pistons W, X, Y and Z. The power pistons A, B, C, D on rotor 31 interdigitate with the power pistons W, X, Y, Z on rotor 29 and all of them are within the annular cylinder 7. Ring sealing means 2 are employed in each piston, the details of which are of no concern to the essentials of the present invention and they are therefore shown diagrammatically by hatching. Thus power cylinder 7 is formed on the outside by the ring 1, on the ends by the heads 3 and 5, and on the inside by the circular portions of the rotors 29 and 31 that lie just within their pistons.

In the heads 5 are provided inlet ports I and exhaust ports E. Conventional fuel carbureting means such as a carburetor or fuel injector (not shown) is connected with the inlet ports I. Ignition means, countersunk in the head 3, are shown at G, preferably of the continuous, so-called glow-type, having a conventional exciting circuit requiring no electrical timing means. If, as may be, a spark-type ignition is used, then suitable timing will be required in the exciting circuit. The glow type is employed for purposes of description.

Fastened to the cylinder heads 3 and 5, respectively, are supporting frameworks 43 and 45, supporting inwardly directed cam tracks 47 and 49, respectively. The following description of reverse-locking parts operative with cam track 49 on the right-hand end of the machine (Fig. 1) is identical with the description applicable to the reverse-locking parts operative with cam track 47 on the left-hand end of the machine. The numbering of these parts will therefore be identical and the one description will apply to both sets of such parts. As will be seen from Fig. 1, some of the parts at the left-hand end of the machine are not shown, in order that the scale of Fig. 1 may be as large as possible in the space available; but it will be understood that the parts not shown at the left-hand end of the machine are the same in form and operation as those shown on the right-hand side.

Referring then to the right-hand side of the machine as shown in Fig. 1, quill 35 of the rotor 31 has attached thereto a hub 51. The corresponding hub 51 at the left-hand end of the machine is attached to quill 33 of

rotor 29. Lock nuts 53 are used for such purposes. Extending from each hub 51 are lugs 55, in which are rotary pintles 57. Clamped to each pinte 57 is an L-shaped follower link 59, one arm of which (Fig. 3) is split, as shown at 61, and provided with a clamping bolt 63 for clamping each arm fast to its pinte. At the end of the other arm of each follower link 59 is a roller follower 65, engageable with cam track 49. Springs 67 maintain engagement between the follower rollers 65 and the cam track 49. Each spring 67 has a bail 69 engaging its respective lug 55 and anchors 71 on the ends of its respective pinte 57, and is wound with tension in the appropriate direction to effect said engagement.

The cam track 49, for the number (eight) of power pistons shown, is of generally square form, having four flats 73 joined by four corner fillets 75. This arrangement permits free rotation of the respective hub 51 with its lugs 55 in one direction (clockwise in Fig. 3, as shown by the curved arrow F). When the parts are in or near the positions shown in Fig. 4, reverse rotation is prevented. This is referred to herein as a reverse-locked position. The reason for the reverse-locking effect is that each compression thrust H is quite close to a perpendicular position relative to its respective flat 73 at a point adjacent its respective fillet 75. This, in view of the tension wound into its respective spring 67, will not allow anticlockwise rotation of the respective follower link 59. It is to be understood that there is a small range of positions near perpendicularity of the vectors H within which range reverse locking can occur. This obviates a harsh impact effect upon reverse locking, resulting in what may be designated a "soft" reverse-locking action, which is conducive to long roller and cam track life. The stated range is measured by only a few degrees.

During clockwise rotation of the respective hub 51 and lugs 55 (Fig. 3), the follower links oscillate in and out around their pintles 57 as the roller followers 65 traverse the cam. It will be understood that, although Fig. 3 shows the reverse-locking cam and follower arrangement on the right-hand end of the machine, the one on the left-hand end involving cam track 47 is the same in form and the cam tracks 47 and 49 are in the same positions relative to the various parts of cylinder 7. Since the respective hubs 51 are attached to the respective quills 35 and 33 of the respective rotors 31 and 29, the rotors, and their attached power pistons (A, B, C, D) and (W, X, Y, Z) respectively have certain reverse-locking positions. The reverse-locking position for rotor 31 is shown in Figs. 2, 6 and 7; that for rotor 29 in Fig. 9. The direction of free rotations for both rotors will accord to downward piston movements at the top of Fig. 1 and upward piston movements at the bottom. This corresponds to clockwise movement in Fig. 3 and anticlockwise movement in Fig. 2. The reverse-locking direction is anticlockwise in Fig. 3 and clockwise in Fig. 2.

Bolted to each hub 51 (see bolts 77) is a spacer ring 81 and a flywheel 79. The bolts also hold the flanges 83 of inner and outer anchoring sleeves 85 and 87 for clamping one end of a helical drive spring 89. The outer sleeve 87 is split and provided with a nut 91. When the nut 91 is run in on the sleeve 87, one end of the spring 89 is gripped. The other end of the spring 89 is anchored between sleeves 93 and 95, the outer one of which is also split for reception of a nut 97 for gripping purposes. The right-hand ends 99 of the anchoring sleeves 93 and 95 are pinned to the shaft 41 (see pin 101, for example).

Shaft 41 is threaded, such as shown at 103, for the reception of a nut 105 which forms a shoulder spaced from the end of the respective quill (35 in this case). In the space is located an end thrust bearing 107. The flywheel and spring driving apparatus just described are duplicated at the left-hand end of the machine, although 70

only partly shown in Fig. 1. Thus rotor 31 is connected at the right to shaft 41 through one spring 89 shown in Fig. 1, and is connected at the left to shaft 41 through another spring 89 which does not appear in Fig. 1, but is identical to the spring 89 and its connections as shown and described.

Reverting to the central portion of the machine near section line 2-2 of Fig. 1, and to Fig. 2, numerals 109 and 111 indicate liner rings attached within the rotors 29 and 31, respectively. As shown in Fig. 1, the abutting ends of the rotors 29 and 31 are cup-shaped and together form a circular cavity within the liners. This cavity surrounds the shaft 41 and is generally numbered 6. In this cavity 6 are four control pistons, two of which (marked L, M) are bolted to the bottom of the cavity part in rotor 31 carrying power pistons A, B, C, D, and the other two of which (marked N, O) are bolted to the bottom of the cavity part in rotor 29 carrying power pistons W, X, Y, Z. All of the bolts for fastening these are not shown, but in Fig. 1 the positions of certain of the bolts 4 are indicated by dotted lines rotated into the plane of the section. It will be noted that only one control piston L on rotor 31 and one control piston N on rotor 29 appear in Fig. 1 (see jogged section line 1-1 on Fig. 2), whereas all of the control pistons L, M, N, O appear in Fig. 2 (see section line 2-2 on Fig. 1). Fig. 2 also shows only some of the bolts 4 used, the remainder being omitted to avoid confusion in the drawings.

All of the pistons on rotor 31 (Fig. 1) are arbitrarily stippled for emphasis; those on rotor 29 are not. For the same reason, in Figs. 6-9 the pistons on rotor 31 are shown solid and those on rotor 29 are dotted.

In the bottom of the cavity within the end of rotor 31 not occupied by the pistons L, M are symmetrically located sector-shaped grooves P, Q (Figs. 2, 4 and 6-9). These are also stippled where exposed, to emphasize that they rotate with pistons A, B, C, D, L and M. In the bottom of the cavity within the end of rotor 29 not occupied by pistons N and O are symmetrically located sector-shaped grooves R, S. These grooves R, S are not stippled but are shown by dotted lines in Figs. 6-9 to indicate that they rotate with pistons W, X, Y, Z, N and O. These also show in Fig. 5 in solid lines. The grooves P and Q show in Fig. 2, but the grooves R and S, being above the plane of this latter section, do not appear. None of the grooves R, S, P or Q appear in solid lines in the Fig. 1 axial section, but dotted representations of P and R have been rotated into the plane of this section for clarifying their radial positions.

As above described, the flanges 25 and 27 of liners 17 and 19 are affixed to the cylinder heads 3 and 5 and are therefore stationary. In flange 27 are located four short arcuate grooves J-1, J-2, J-3 and J-4 (see Figs. 2, 4 and 6-9). These (as indicated in Fig. 4) become connected at certain times with the inside of the cavity by means of holes 113, drilled through the radial part of the rotor 31 that forms one end of the cavity 6. The holes 113 connect permanently respectively with passages 115 in the pistons L and M, which are bolted to the rotor 31. The members of each pair of passages 115 respectively extend to the opposite face of the piston L or M, as the case may be. For convenience in manufacture, passages 115 are right-angular grooves cut into the outer peripheries of the pistons.

In the other flange 25 are located four short arcuate grooves K-1, K-2, K-3 and K-4 (see Figs. 5-9). These as shown in Fig. 5, are connected at certain times with the inside of the cavity 6 by means of holes 117, drilled through the radial part of the rotor 29 that forms the other end of the cavity. The holes 117 respectively connect permanently with passages 119 in the control pistons N and O, which are bolted to the rotor 29. The members of each pair of passages 119 respectively extend to the opposite face of the piston N or O, as the case may be. For manufacturing convenience, these passages 119

are also right-angular grooves cut into the outer peripheries of the pistons.

In Fig. 1, groove J-1, one hole 113 and one passage 115 have been rotated into the plane of the Fig. 1 section and shown in dotted lines. Also in Fig. 1, groove K-1, one hole 117 and one passage 119 have been rotated into the plane of the Fig. 1 section and shown in dotted lines. This is for the purpose of showing the relative axial positions of these parts. Figs. 2 and 6-9 will show their relative angular positions in connection with the description to be given. The developed views of Figs. 4 and 5 are illustrative details of them.

Referring to Figs. 2-9, operation is as follows, keeping in mind that the rotary directional dart F of Fig. 3 will appear in the reverse direction as shown in Figs. 2 and 6-9:

Starting with the parts as shown in Figs. 2 and 6 (the latter being diagrammatic), the rotor 31 carrying pistons A, B, C, D, L, M is taken to be in reverse-locked position (see the reverse-locked position of the followers 59, 65 on the cam track 49 in Fig. 3). An expansion (explosion) event is occurring both between pistons A and W and between pistons C and Y. An exhaust event is occurring both between pistons W and B and between pistons Y and D. A suction or fuel injection event is occurring both between pistons B and X and between pistons D and Z. A compression event is occurring both between pistons Z and A and between pistons X and C. The control pistons L, M on rotor 31 are in symmetrical bisecting positions over the respective grooves R and S in rotor 29 (Fig. 6), providing free communication from front to rear of each piston. The control pistons N and O on rotor 29 are in symmetrical bisecting positions over the respective grooves P and Q in rotor 31, also providing free communication from front to rear of these pistons respectively. The passages 115 of control piston L are stationary and through holes 113 are registered with stationary groove J-1, thereby affording an auxiliary restricted fluid communication from one side to the other of piston L. The passages 115 in stationary control piston M are registered through holes 113 with the stationary groove J-3, forming an auxiliary restricted communication from one side to the other of the piston M. The stationary grooves J-2 and J-4 are not at this time in registry with any other passages. None of the stationary grooves K-1, K-2, K-3, K-4 is in registry with any of the passages 119 in pistons N and O.

Assuming now that the rotor 29 advances anticlockwise from the Fig. 6 to the Fig. 7 position, further gaseous compression (or gaseous collision) occurs between pistons Z and A and between pistons X and C, rotor 31 with its pistons A, B, C, D, L, M being reverse-locked under reaction from the expansion occurring between pistons A and W on the one hand, and Y and C on the other hand. During this action, the hydraulic control pistons O and N advance upon stationary control pistons L and M, respectively, thus squeezing hydraulic fluid from front to rear of the pistons N and O, respectively, through the grooves P, Q, R and S. Fluid is also forced past pistons L and M via ports 115, 113, J-1 and 115, 113, J-3 respectively. Since the fronts of the pistons N and O are approaching the anticlockwise ends of the grooves P and Q, respectively, increased throttling of flow occurs from fronts to rears of pistons N, O, so that in addition to the gaseous collision process occurring between pistons Z and A and between X and C, there will occur an increasingly forceful hydraulic collision process between the control pistons N and M on the one hand, and between O and L on the other hand. Thus the gaseous collision process going on in the power cylinder 7 is assisted by the hydraulic collision process in the control cavity between rotors 29 and 31.

The next step in the process will be seen by comparing Figs. 7 and 8. In proceeding from Fig. 7 to Fig. 8, the rotor 29 continues to move and the sum of the said gas-

eous collision and hydraulic collision processes causes angular momentum to be transferred from the rotating system connected with rotor 29 to that connected with rotor 31, and ultimately moving the latter from its reverse-locked position. This moves pistons A, B, C, D, L and M as indicated in Fig. 8. But during the first part of this operation the rotor 29 is still overtaking the rotor 31 as the parts first approach the Fig. 8 configuration but this does not continue for long. However, as this overtaking process proceeds from the Fig. 7 configuration to the Fig. 8 configuration, the passages 115, 113 associated with pistons L and M, respectively, get out of register with respect to the grooves J-1, J-3, respectively, so that the remaining charge of hydraulic fluid between pistons O and L on the one hand, and between pistons N and M on the other hand, becomes completely trapped. The result is a substantially inelastic connection between the rotors 29 and 31 which carries them together in an anticlockwise direction during the action as depicted in Fig. 8. The two rotor systems then move as one system, with all of the angular momentum that was in the system connected with rotor 29, divided between the systems connected to 29 and 31. The result is that (Fig. 8) both move with the same angular velocity equal to half the maximum velocity of the rotor 29, the moments of inertia of both systems being the same, since their structures are identical.

In the Fig. 8 configuration, the rotor 29 is moving into the range of reverse-locking activity of its reverse-locking elements 59, 65, and ultimately moves up to the reverse-locking position such as shown in Fig. 9. By this time, as shown in Fig. 8, the ignition devices have been exposed to the compressed charges in the clearance spaces between pistons Z and A and X and C, respectively, thus having ignited them for expansion by the time pistons Z and X arrive at their final reverse-locked positions, as shown in Fig. 9. This second expansion event initiates a second cycle.

Thus it will be seen that in Fig. 9 the rotor 29 has moved into reverse-locked position wherein its pistons Z and X cover the ignition devices G, and the expansion event which proceeds between pistons Z and A and between X and C places the rotor 31 in the position that rotor 29 had initially in the Fig. 6 configuration. It will also be noted that the passages 119, 117 associated with control pistons O and N, respectively, have come into registry with the stationary grooves K-1 and K-3, respectively. This has the effect of connecting the spaces on opposite sides of the control pistons O and N on rotor 29 when reverse locked. Also, the control pistons L and M on rotor 31 are in bisecting positions over grooves R and S, respectively, which form fluid passages from the fronts to rears of these pistons L and M. Thus is broken the temporary inelastic hydraulic connection between rotors which assured that the overtaking rotor 29 would enter the reverse-locking range in displacing the reverse-locked rotor 31.

The above has described a sequence of events requiring 45° of motion of each of the rotors 29 and 31. This resulted in interchange of the rotor positions (compare Figs. 6 and 9). The machine is then as in Fig. 9.

The operation for the second cycle is similar to that of the operation above given for the first cycle, except that the relations of movements of the power pistons A, B, C, D and W, X, Y, Z are interchanged; likewise, the movements between the control pistons L and M and grooves R and S on the one hand, and the movements between the control pistons O and N and the grooves P and Q on the other hand are interchanged. Nevertheless, the actions on the power events in power cylinder 7 by the control events in the cavity 6 are the same. For example, consider in Fig. 9 that the rotor 31 (pistons A, B, C, D) will advance on rotor 29 (pistons W, X, Y, Z). This advances control piston M toward the stationary control piston O, and at the same time moves the groove Q anti-

clockwise under the piston O. Thus fluid is squeezed from between control pistons M and O into location between piston O and receding piston L. This, for example, at first occurs through the groove Q, but gradually the entry end of this groove Q is being throttled as it moves under piston O. This gradually shuts off the flow, so as to provide the increasing hydraulic collision assistance to the gaseous collision event occurring between power pistons D and Z. At the time of shut-off of this flow through groove Q, hydraulic flow will occur past control piston O through its passages 119, 117 and registered groove K-1. Ultimately, as rotor 29 again moves, passages 119, 117 in piston O leave groove K-1 and the two rotors 29, 31 move in inelastic hydraulic connection with one another until passages 115, 113 of piston M register with groove J-4, whereupon this connection is broken and rotor 29 released from rotor 31 as the latter again reaches a position within its reverse-locking range.

Summarizing the operation, eight power cycles occur for each revolution of the power shaft. The first, third, fifth and seventh cycles operate by overrunning action of the pistons and porting grooves connected with rotor 29 with respect to the pistons and porting grooves connected with stationary rotor 31; and the second, fourth, sixth and eighth cycles operate with similar results by overrunning action of the pistons and porting grooves connected with rotor 31 with respect to the pistons and porting grooves connected with stationary rotor 29. During the first, third, fifth and seventh cycles, the passages 115, 113 of pistons L and M cooperate with stationary grooves J-1, J-2, J-3 and J-4. During the second, fourth, sixth and eighth cycles, the passages 119, 117 of pistons N and O cooperate with stationary grooves K-1, K-2, K-3 and K-4.

It will be understood that the reverse-locking parts, including 55, 59 and 65, as shown in Fig. 3 for rotor 31 are duplicated on rotor 29 at the other end of the machine, but not shown. In the latter case the reverse-locking parts corresponding to parts 59 and 65 have the same structural relationship to pistons W, X, Y, Z on rotor 29 as the parts 5 and 65 have relative to pistons A, B, C, D on rotor 31.

As each rotor is intermittently driven under an expansion event and moves its follower system 51, 55, 57, 59, 65 along with its flywheel 79, it drives the shaft 41 by winding up its respective connecting spring 89, the other spring 89 connecting the other rotor system with the shaft unwinding. The springs therefore form means whereby alternately energy is delivered from the respective rotors to the common shaft 41 and permit alternate overrunning of one rotor with respect to the other. In effect they integrate energy at the shaft received alternately from the rotors.

The cavity between rotors 29 and 31 is filled with a hydraulic fluid lubricant, which may be subject to leakage. Inlet supply ports into the cavity 6 between rotors for hydraulic fluid are shown at numerals 121 on rotor 31 in Figs. 1 and 2. Corresponding outlet openings 127 are provided in rotor 29. The radial positions of openings 121, 127 are shown in Fig. 1 by rotation of one each into the plane of the section. All of the openings 121 are supplied from a groove 123 around the quill 35, an inlet connection for this groove being shown at 125. All of openings 127 are connected to a groove 129 having an outlet 131. By carrying a suitable pressure head on the inlet 125, circulation may be effected and loss of lubricant from the cavity between rotors 29 and 31 may be made up.

It will be understood that while various grooves have been referred to as forming certain passages, slots, cored or drilled holes and the like may be used, and these are therefore to be considered as equivalents. It is also to be noted that the type of rotary engine to which the invention applies is sometimes referred to in the art as an alternating piston engine, meaning that groups of inter-

digitating power pistons on rotors in a toroidal or annular cylinder move alternately in carrying out thermodynamic cyclic processes. In the same sense, the groups of control pistons L, M and N, O described herein are to be considered as interdigitating in the cavity 6 and being of the alternating type. The term alternating is also used in the sense that the pistons of one rotor alternate in position with respect to the pistons on the other rotor. This is also true of certain passages such as the grooves P, Q, R, S. In the case of grooves J-1, J-2, J-3, J-4 and K-1, K-2, K-3, K-4, the members of the respective groups alternate in position, peripherally considered.

While the passages 119, 117 (through pistons N and O) and the passages 115, 113 (through pistons L and M) are shown as grooves on the piston peripheries, it will be understood that these may be in the form of drilled or cored passages from one wall to another of the respective pistons. Also, while the grooves P and Q in rotor 31 and the grooves R and S in rotor 29 are shown as open throughout their lengths, it will be understood that these also may be cored passages with open ends. The same is true of the grooves J-1, J-2, J-3 and J-4, and K-1, K-2, K-3 and K-4. In this respect the terms grooves, holes, ports, slots and the like are to be considered as synonymous.

The engine above described is of the so-called unidirectional free piston variety in the sense that the motion of the cooperating pistons relative to one another has no positive constraint through any mechanical linkage. It will be observed, on the other hand, that the rotary systems to which the power pistons are attached carry control means in the forms of the pistons L, M, N, O which are adapted to be locked for equal movements thereof and of the rotary systems during a portion of the gas-buffered collision event that occurs during gas compression between the power pistons. Timing means for locking is effected by the hydraulic porting, which is controlled by the relative motions between the rotary systems and between them and the frame.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. Rotary apparatus comprising an assembly of a stationary support for an annular cylinder and at least two cooperating rotary systems, having interdigitated power pistons in said cylinder, wherein alternately each system advances upon the other to effect a gas-buffered collision event between said power pistons, said rotary systems also including interdigitated control pistons in a liquid medium located in a cavity formed by the rotary systems, and fluid porting means arranged between the stationary support, the rotary systems and the control pistons, adapted upon movements between the rotary systems relative to each other and the support, first to produce a liquid-buffered collision event between the control pistons during a gas-buffered collision event between the power pistons, whereby the latter event is assisted by the former event in partially transferring momentum from one rotary system to the other, second to close whereby the rotary systems move together in a substantially inelastic relationship without substantial transfer of momentum between them, and third to reopen and release one rotary system from the other during an expansion event and substantial completion of momentum transfer.

2. Rotary apparatus made according to claim 1, wherein said porting means includes a first set of recesses formed in said rotary systems and is traversed by said control pistons to effect said liquid-buffered collision

event, and wherein a second set of relatively movable recesses formed in said stationary support and in the control pistons effect said closure and reopening to effect said inelastic movement and release.

3. Rotary apparatus made according to claim 2, wherein the traversal by said control pistons of said first set of recesses effects gradually varying throttling action and wherein said second set of relatively movable recesses when open produce a maximum of throttling action.

4. Rotary apparatus comprising an assembly of a stationary support for an annular cylinder and at least two cooperating rotary systems having interdigitated power pistons in said cylinder, wherein alternately each system may advance upon the other to effect a gas-buffered collision event between said power pistons and to reach a reverse-locked position, said rotary systems also including interdigitated control pistons in a liquid medium located in a cavity formed by and located between the rotary systems, and fluid porting means arranged between the stationary support, the rotary systems and the control pistons, adapted upon relative movements between the rotary systems relative to each other and the support, first to produce a liquid-buffered collision event between the control pistons during a gas-buffered collision event between the power pistons, whereby the latter event is assisted by the former event in elasticity transferring momentum from one rotary system to the other, second to close whereby the rotary systems move together as a substantially inelastically related pair without momentum transfer, whereby one system is positively replaced by the other in a reverse-locked position, and third to reopen and release one rotary system from its inelastic relationship to the other during an expansion event after said replacement.

5. Rotary apparatus made according to claim 4, wherein said porting means includes elements operative according to the relative rotations of the systems adapted to graduate the driving action of said liquid-buffered collision event from a minimum to a maximum prior to the start of said inelastic relationship.

6. Rotary apparatus comprising an assembly of a stationary support for an annular cylinder and at least two cooperating rotary systems having interdigitated power pistons in said cylinder, reverse-locking means for the respective systems wherein alternately each system may advance upon the other to effect a gas-buffered momentum transferring collision event between said power pistons and to interchange reverse-locked positions of the systems, said rotary systems also including interdigitated control pistons in a liquid medium located in a cavity formed by and located between the rotary systems, and fluid porting means arranged between the stationary support, the rotary systems and the control pistons, adapted upon relative movements between the rotary systems relative to each other and the support, first to produce a liquid-buffered collision event between the control pistons during a gas-buffered collision event between the power pistons, whereby the latter event is assisted by the former event in elastically transferring momentum from one rotary system to the other, second to close whereby the rotary systems move together as a substantially inelastically related pair without momentum transfer, whereby one system is positively replaced by the other in a reverse-locked position, and third to reopen to release one rotary system from its inelastic relationship to the other during an expansion event after said replacement, said expansion event with one of said reverse-locking means locking said one system and transferring all momentum to the other.

7. Rotary apparatus made according to claim 6, wherein said porting means includes elements operative according to the relative rotations of the systems adapted increasingly to graduate the effect of said liquid-buffered collision event upon said gas-buffered collision event.

8. A rotary expansion engine comprising a frame, a power shaft, a toroidal cylinder attached to the frame and

surrounding the shaft, a pair of rotors, each rotor having at least one power piston in the cylinder, means for producing power events between power pistons on the rotors, means adapted alternately to reverse lock the rotors in response to said power events, and driving means between each rotor and the shaft, said rotors providing between them a circular cavity for hydraulic control fluid and respectively carrying at least one rotary control piston which is movable relative to the other in said cavity, and fluid porting means arranged between the frame, the rotors and the fronts and backs of the control pistons, adapted first to move toward a closed position during a compression event between an advancing and a reverse-locked rotor to produce hydraulic resistance between them in addition to gaseous compression resistance, whereby the reverse-locked rotor is driven from its reverse-locked position by the advancing rotor, second to close said hydraulic porting means whereby both rotors move together in a substantially hydraulically locked condition until an expansion event is reached after a reverse-locked position is reached by the advancing rotor, and third to open to release the formerly reverse-locked rotor for recession from the reverse-locked position in response to the expansion event reacting against the other rotor at its reverse-locked position.

9. Hydraulic control means for collision processes between abutting relatively moving rotors of alternating piston engines, said rotors being adapted alternately to turn in a stationary frame of said engine; comprising circular recesses in the abutted portions of the rotors together forming a circular cavity adapted to be filled with hydraulic fluid, said frame having separate groups of recesses adjacent said rotors respectively, the recesses in one group alternating in peripheral positions with the recesses in the other group, at least one control piston attached to each rotor and having alternating positions and movements within the cavity, at least one recess on each rotor cooperating movably with a control piston on the other rotor during alternating piston movements so as intermittently to transfer fluid in the cavity from one side to the other of the cooperating control piston, each control piston on each rotor having a passage adapted in response to rotor movements to connect intermittently with successive recesses in one of said groups.

10. Hydraulic control means for collision processes between abutting rotors of alternating piston engines, said rotors being adapted alternately to turn in a stationary frame of said engine; comprising circular recesses in the abutted portions of the rotors together forming a circular cavity adapted to be filled with hydraulic fluid, said frame having groups of recesses in portions adjacent said rotors respectively, the members of each group of recesses alternating in peripheral positions relative to the members of the other group, groups of control pistons attached respectively to the rotors within the cavity, members of each group of control pistons having alternating positions and movements within the cavity with respect to the members of the other group, groups of additional recesses on each rotor, the members of each additional group alternating in position with respect to the control pistons on the respective rotor, the members of each group of said additional recesses in one rotor cooperating movably with the members of the group of control pistons on the other rotor during alternating rotor movements so as intermittently to transfer fluid in the cavity from one side to the other of each control piston, each control piston of each group having passages adapted in response to rotor movements to register intermittently through continuations thereof in the respective rotors with the respective groups of recesses in the frame.

11. Hydraulic control means for collision processes between abutting rotors of alternating piston engines, said rotors being adapted alternately to turn in a stationary frame of said engine; comprising circular recesses in the abutted portions of the rotors together forming a circular

cavity having end walls and adapted to be filled with hydraulic fluid, said frame having groups of four fixed recesses in portions adjacent the outsides of said end walls respectively, the members of each group of fixed recesses alternating in peripheral positions relative to the members of the other group, oppositely located pairs of control pistons attached respectively to the rotors, members of each pair of control pistons having alternating positions and movements within the cavity with respect to the members of the other pair of control pistons, pairs of recesses on each rotor, the members of each pair of control rotor recesses alternating in position with respect to the control pistons on the respective rotor, each pair of grooves in one rotor cooperating movably with the pair of control pistons on the other rotor during alternating control piston movements so as intermittently to transfer fluid in the cavity from one side to the other of each control piston, each control piston having passages adapted in response to rotor movements to register through openings in said end walls with the respective groups of four grooves in the frame.

12. Rotary apparatus comprising an assembly of a stationary support for an annular cylinder and at least two cooperating rotary systems having interdigitated power pistons in said cylinder, wherein alternately each system advances upon the other to effect a gas-buffered compression event between said power pistons, control means carried by and respectively movable with the rotary systems, and means adapted to lock said control means together for substantially equal movements thereof and of said rotary systems to which they are attached during a portion of said compression event.

13. Rotary apparatus comprising an assembly of a stationary support for an annular cylinder and at least two cooperating rotary systems having interdigitated power pistons in said cylinder, wherein alternately each system effects an advancing movement upon the other in response to an expansion event between certain sets of said power pistons to effect a gas-buffered compression event between other sets of said power pistons, control means carried by and respectively movable with the rotary systems, locking means adapted to lock said control means together for substantially equal movements thereof and of said rotary systems to which they are attached, and timing means responsive to said advancing movements adapted to actuate said locking means during a portion of said compression event.

14. Rotary apparatus comprising an assembly of a stationary support for an annular cylinder and at least two cooperating rotary systems having interdigitated power pistons in said cylinder, wherein alternately each system advances upon the other to effect a gas-buffered compression event between said power pistons, control means comprising control pistons carried by and respectively movable with the rotary systems, hydraulic means adapted to lock said control pistons together for substantially equal movements thereof and of said rotary systems to which they are attached during a portion of said compression event, and hydraulic port means timed by

the motions of said rotary systems adapted to actuate said hydraulic locking means to lock together said control pistons and the rotary systems to which the control pistons are attached during a portion of said compression event.

15. Rotary apparatus comprising an assembly of a stationary support for an annular cylinder and at least two cooperating rotary systems having interdigitated power pistons in said cylinder, wherein alternately and 10 repeatedly each system advances upon the other to effect gas-buffered compression events between said power pistons, control means comprising control pistons carried by and respectively movable with the rotary systems, means adapted to interconnect said control pistons to assume substantially equal movements thereof and of said rotary systems to which they are attached, and hydraulic means timed by the motions of said rotary systems adapted to effect inter-connection of said control pistons and therefore of the rotary systems only during a portion of each of said compression events.

16. Rotary apparatus comprising an assembly of a stationary support for an annular cylinder and at least two cooperating rotary systems having interdigitated power pistons in said cylinder, wherein alternately each system 25 advances upon the other to effect a gas-buffered compression event between said power pistons, connective means carried by and respectively movable with the rotary systems, means adapted to connect said connective means for effecting substantially equal movements thereof and of said rotary systems to which they are attached during a portion of said compression event, and means timed by the motions of said rotary systems adapted to effect connection of said connective means and therefore of the rotary systems during a portion of said compression event.

17. Hydraulic control means for gaseous collision processes occurring between cooperating relatively moving rotors of engines of the alternating power piston type; comprising groups of stationary control slots in opposite ends of a space formed by opposite stationary parts of the engine, relatively movable rotors having rotor members in said space and between them forming a pocket, each rotor member having attached control pistons alternating with interdigitated control pistons of the other in said pocket and each rotor member having alternating grooves in said pocket cooperating respectively with the control pistons of the other adapted for liquid transfer across the pistons, said control pistons having liquid transfer ports connecting their front and rear faces through said rotor members for timed connections with said stationary slots during rotor movements, adapted to augment said fluid transfer.
